UNITED STATES PATENT OFFICE.

MAXIMILLIAN W. WUESTHOFF, OF SAN FRANCISCO, CALIFORNIA.

DESIGN FOR A SPOUT FOR BATH AND LAVATORY FIXTURES.

Application filed November 27, 1925. Serial No. 15,555. Term of patent 14 years.

To all whom it may concern:

Be it known that I, MAXIMILLIAN W. WUESTHOFF, a citizen of the United States, residing at the city and county of San Francisco, State of California, have invented a new, original, and ornamental Design for a Spout for Bath and Lavatory Fixtures, of which the following is a specification, reference being had to the accompanying drawings, forming part thereof.

Fig. 1 shows a perspective view of a spout embodying my design.

Fig. 2 shows a front elevation of the same.

I claim:

The ornamental design for a spout for bath and lavatory fixtures, substantially as shown.

MAXIMILLIAN W. WUESTHOFF.
